UNITED STATES PATENT OFFICE

158,377

UTENSIL WALL BRACKET

Elmer P. Haglund, Burbank, Calif.

Application March 1, 1949, Serial No. 1,157

Term of patent 14 years

(Cl. D44—26)

To all whom it may concern:

Be it known that I, Elmer P. Haglund, a citizen of the United States and a resident of the city of Burbank, in the county of Los Angeles and State of California, have invented a new, original, and ornamental Design for a Utensil Wall Bracket, of which the following is a specification, reference being had to the accompanying drawings, forming part thereof, in which:

Fig. 1 is a perspective view, in open position, of a utensil wall bracket, showing my new design;

Fig. 2 is a front view, in open position;

Fig. 3 is a side view, in open position, and

Fig. 4 is another side view in closed position thereof.

I claim:

The ornamental design for a utensil wall bracket, as shown.

ELMER P. HAGLUND.
